UNITED STATES PATENT OFFICE.

CHARLES D. BRANDT, OF NEW YORK, N. Y., ASSIGNOR OF ONE-HALF TO EUGENE J. SCHWEIZER, OF RIDGEWOOD, NEW YORK.

PUMP-STIRRUP.

1,339,943.

Specification of Letters Patent. Patented May 11, 1920.

Application filed October 4, 1919. Serial No. 328,497.

To all whom it may concern:

Be it known that I, CHARLES D. BRANDT, a citizen of the United States, and a resident of Richmond Hill, borough and county 5 of Queens, city and State of New York, have invented certain new and useful Improvements in Pump-Stirrups, of which the following is a specification.

My invention relates to pumps and more 10 particularly to air pumps for inflating pneumatic tires and the like and has for its object to provide a folding stirrup arrangement in which the stirrups are pivotally mounted and secured in position in a 15 novel and efficient manner and in which the necessity for drilling and drill-holes is avoided. My invention will be fully described hereinafter and the features of novelty will be pointed out in the appended 20 claims.

For illustrative and descriptive purposes, a specific embodiment of my invention is shown in the accompanying drawings in which Figure 1 is an elevation; Fig. 2 is 25 a vertical section on the line 2—2 of Fig. 1 and Fig. 3 is a horizontal section on the line 3—3 of Fig. 2.

The pump itself may be of any well known and customary construction and, as 30 shown, comprises the usual barrel 5 in which the piston is reciprocated, by means of a suitable piston rod and handle, in any recognized manner, these latter parts being omitted as unnecessary to the proper illustration of the invention. The pump further is provided with the usual connection 35 6 for the detachable accommodation of the customary flexible hose whereby the pump is operatively connected with the pneumatic tire or other element to be inflated. As is generally customary, the one end of 40 the barrel 5 is fitted and secured in a cap 7 with the interior with which the connection 6 is in communication.

In the present instance this cup 7 is continued in an axial direction in the form 45 of a neck 8 which is constructed with a main recess 9 extending diametrically through said neck 8 and in an axial direction as shown in Fig. 2. Auxiliary recesses 50 10 extend in correlated pairs in opposite directions toward the axis of the pump at intermediate portions of said neck and communicate with the main recesses 9 as shown 55 in Figs. 1 and 3. The outer ends of said

auxiliary recesses 10 are open and interrupt the periphery of said neck, while the inner ends thereof are closed, the inward length of said auxiliary recesses 10 from said periphery being predetermined as will be 60 more fully described hereinafter.

The construction further includes stirrup members 11 and 12 having foot rests 13 and toothed segments 14 arranged to mesh together, as shown in Fig. 2. The stirrup 65 members 11 and 12 are each provided with trunnions 15 arranged in diametrically opposite pairs on each stirrup member and preferably forming integral parts thereof. In the assembled condition of the parts these 70 trunnions are seated in the auxiliary recesses 10 and constitute the pivots upon which the stirrup members 11 and 12 are swung to and from their operative and inoperative positions. The stirrup members 75 11 and 12 are accommodated, in the main recess 9, which has a transverse width just sufficient to avoid interference with the pivotal movements of said members and to prevent undue vibration thereof, said foot rests 80 13 being located exteriorly of the main recess 9 as shown. The trunnions 15 are dimensioned to fit the auxiliary recesses 10 without unnecessary looseness and the inward length of the latter is such as to provide 85 for the proper meshing of the toothed segments 14, the inner ends of said auxiliary recesses 10 being located so as to constitute efficient bearings for said trunnions. The stirrup members 11 and 12 are maintained 90 in position and the trunnions 15 are held against unintentional removal from the auxiliary recesses 10 by means of a resilient ring 16 of suitable material fitted into an annular channel 17 and extending circumferentially about the neck 8. The dimensions and location of the parts are so arranged that the ring 16 bears against the segmental surfaces 18 of the stirrup members 11 and 12 and thus secures the latter 95 100 against unintentional dislocation; the stirrup members 11 and 12 are formed with pockets 19 into which the ring 16 fits when the stirrup members are in their inoperative positions. In addition the stirrup members 11 and 12 may be provided with opposed surfaces 20 which, in the operative position of said members, abut and thus increase the rigidity of the construction. 105

In assembling the parts the stirrup mem- 110

bers 11 and 12 are inserted into the main recess 9 from opposite sides of the neck 8, with the trunnions 15 in registry with the auxiliary recesses 10 and moving inwardly 5 in the same, until the toothed segments 14 are in proper mesh; this operation is preferably carried out with the foot rests 13 in their operative positions. The ring 16 is then sprung or otherwise fitted into the 10 channel 17 to maintain the parts in their assembled condition.

The foot rests 13 and with them the stirrup members 11 and 12 may now be pivotally swung on the trunnions 15 to and 15 from their operative and inoperative positions, the pressure of the ring 16 upon the segmental surfaces 18 preventing undue vibration of said members and foot rests during such movements. When the stirrup 20 members 11 and 12 are in their operative positions, the foot rests 13 extend in opposite directions, in registry with each other and may thus be placed upon a floor, roadway or the like to provide rests for the feet 25 whereby the pump is held in place against upward movement when in use. The co-operating surfaces 20, by being pressed against each other as the stirrup members 11 and 12 tend to pivotally swing when the 30 pump piston is drawn upwardly, serve to increase the rigidity of the structure and its efficiency as a pump. In the inoperative positions of the stirrup members 11 and 12 the ring 16 lies within the pockets 19 while 35 the foot rests 13 extend lengthwise of the barrel 5 and close thereto so as to occupy a minimum of space and to provide a compact arrangement in the folded condition of the parts.

40 The improved construction does away with machining of the parts and avoids the necessity for drilling rivet or pin-holes thus doing away with the use of rivets or pins which, under the strains incident to use, are 45 likely to work loose and thus reduce the efficiency of the pump as a mechanical structure. The recesses, main and auxiliary, are easily cut or otherwise produced in the neck, while the trunnions are readily fashioned 50 upon the stirrup members thus reducing the cost of production to a minimum and increasing the field of usefulness of the pump by making it available to a greater number of users because of its low cost.

55 The parts are quickly assembled and as quickly disassembled, thus reducing the cost of repairs and upkeep.

Various changes in the form shown and described may be made within the scope of

the claims without departing from the spirit 60 of my invention.

I claim:

1. The combination of an air pump provided with inwardly extending open-ended recesses, arranged in coöperating pairs, a 65 pair of stirrup members extending between said recesses, trunnions on said stirrup members extending into said recesses and constituting pivots for said members and means whereby said trunnions are maintained in 70 said recesses.

2. The combination of an air pump, a cap at one end thereof having an axially extending main recess and transverse auxiliary recesses arranged in coöperating pairs and 75 communicating with said main recess, said auxiliary recesses being open at their outer ends, stirrup members located in said main recess and between each pair of auxiliary recesses and movable to and from an operative 80 position, trunnions on said stirrup members extending into said auxiliary recesses and constituting pivots for said members, an annular ring obstructing the open ends of said auxiliary recesses and engaging 85 said stirrup members whereby said trunnions are maintained against removal from said auxiliary recesses and segmental gears on said stirrup members and meshing with each other whereby said members are pivotally movable in unison.

3. The combination of an air pump, a cap at one end thereof having an axially extending main recess and transverse auxiliary recesses arranged in coöperating pairs and 95 communicating with said main recess, said auxiliary recesses being open at their outer ends, stirrup members located in said main recess and between each pair of auxiliary recesses and movable to and from an operative 100 position, trunnions on said stirrup members extending into said auxiliary recesses and constituting pivots for said members, an annular ring obstructing the open ends of said auxiliary recesses and engaging 105 said stirrup members whereby said trunnions are maintained against removal from said auxiliary recesses, said stirrup members having pockets for the accommodation of said ring when the stirrup members are in their inoperative positions and segmental gears on 110 said stirrup members and meshing with each other whereby said members are pivotally movable in unison.

In testimony whereof I have hereunto set 115 my hand.

CHARLES D. BRANDT.
